Primary Examiner — T Chase Nelson*Assistant Examiner* — Kelly L Gross(74) *Attorney, Agent, or Firm* — Lawrence N. Ginsberg(57) **CLAIM**

The ornamental design for an orthopedic device with multiple q-angle adjusters, as shown and described.

DESCRIPTION

FIG. 1 is a front perspective view of an embodiment of the orthopedic device with multiple q-angle adjusters, showing our new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken line showing of portions of the orthopedic device with multiple q-angle adjusters, forms no part of the claimed design.
